(57) **CLAIM**

The ornamental design for a swimming oar, as shown and described.

DESCRIPTION

FIG. 1 is a top, perspective view of a swimming showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a top perspective view thereof with straps shown in phantom lines.

The broken lines showing straps in FIG. 8 are for illustrative purposes only and do not form part of the claimed design.
